(57) **CLAIM**

The ornamental design for a chair, as shown and described.

DESCRIPTION

FIG. 1 is a front perspective view of a chair showing my new design;

FIG. 2 is a front elevational view thereof;

FIG. 3 is a rear elevational view thereof;

FIG. 4 is a left side elevational view thereof, the right side elevational view being essentially a mirror image thereof;

FIG. 5 is a top plan view thereof;

FIG. 6 is a bottom plan view thereof;

FIG. 7 is a front elevational view of a second embodiment of a chair which is essentially identical to the one shown in FIGS. 1-6, except that the seat is made from a different cover material, and the back, arm and head rests are also made from a similar cover material;

FIG. 8 is a front elevational view of a third embodiment of a chair which is essentially identical to the one shown in FIGS. 1-6, except that the right arm rest is replaced by a tray;

FIG. 9 is a right side elevational view of the chair shown in FIG. 8; and,

FIG. 10 is a top plan view of the chair shown in FIGS. 8 and 9.
